UNITED STATES PATENT OFFICE.

DAVID STONE, OF NEW YORK, N. Y.

DESIGN FOR A BUCKLE.

SPECIFICATION forming part of Design No. 24,444, dated July 2, 1895.

Application filed May 18, 1895. Serial No. 549,838. Term of patent 7 years.

To all whom it may concern:

Be it known that I, DAVID STONE, a citizen of the United States, residing at New York, in the county of New York and State of New York, have invented and produced a new and original Design for Buckles, of which the following is a specification, reference being had to the accompanying drawings, in which—

Figure 1 shows a plan or face view of a buckle containing my new design. Fig. 2 is a view of the rear face or side thereof.

The leading or characteristic feature of my design consists in the buckle-frame having the ornamentation shown, bearing in the central field thereof the representation of a bicycle.

Referring to the drawings, A represents the face of the buckle. Around the outer portion or edges is a border, as shown at D.

B represents the central field or portion of the buckle-face, bearing thereon or therein the representation or figure of a bicycle C.

What I claim as new, and desire to secure by Design Letters Patent, is—

The design for a buckle herein shown and described.

DAVID STONE.
